MOVIE CAMERA OR THE LIKE

David Elwood Hansen, Rochester, N.Y., assignor to Eastman Kodak Company, Rochester, N.Y., a corporation of New Jersey

Filed Aug. 23, 1968, Ser. No. 13,250

Term of patent 14 years

Int. Cl. D16—02

U.S. Cl. D61—1

FIG. 1 is a front-corner perspective view of a design for a movie camera or the like showing the front, top and one side thereof; and

FIG. 2 is a perspective view of the design of FIG. 1 from the back-corner diagonally opposite from the corner depicted in FIG. 1, showing the back, bottom and other side thereof.

I claim:

The ornamental design for a movie camera or the like, as shown.
